UNITED STATES PATENT OFFICE

94,567

DESIGN FOR A NUT CRACKER

Mathias Redlinger, Freeport, Ill.

Application November 21, 1934, Serial No. 54,104

Term of patent 7 years

To all whom it may concern:

Be it known that I, Mathias Redlinger, a citizen of the United States, residing at Freeport, in the county of Stephenson and State of Illinois, have invented a new, original, and ornamental Design for a Nut Cracker, of which the following is a specification, reference being had to the accompanying drawing, forming part thereof.

In the drawing, the figure is a perspective view of a nut cracker showing my new design.

I claim:

The ornamental design for a nut cracker substantially as shown.

MATHIAS REDLINGER.
